(57) **CLAIM**

The ornamental design for a bingo dauber, as shown and described.

DESCRIPTION

FIG. 1 is a front elevation view of a bingo dauber showing my new design illustrated with a cap and a sponge separated for clarity;

FIG. 2 is a rear elevation view thereof;

FIG. 3 is a right elevation view thereof, the opposite being a mirror image of the shown;

FIG. 4 is a top plan view thereof;

FIG. 5 is a bottom plan view thereof;

FIG. 6 is an isometric view thereof; and,

FIG. 7 is a cross-sectional view taken along line 7-7 of FIG. 3; and,

FIG. 8 is a cross-sectional view taken along line 8-8 of FIG. 3. The broken lines in FIG. 6 of the drawings depict environmental subject matter only and form no part of the claimed design.
